UNITED STATES PATENT OFFICE.

WILLIAM J. DONNELLY, OF BUTTE, MONTANA.

DESIGN FOR LINOLEUM.

58,556.

Specification for Design.

Patented Aug. 2, 1921.

Application filed August 27, 1919. Serial No. 320,315. Term of patent 14 years.

To all whom it may concern:

Be it known that I, WILLIAM J. DONNELLY, a citizen of the United States, residing at Butte, in the county of Silver Bow and State of Montana, have invented a new, original, and ornamental Design for Linoleum, of which the following is a specification, reference being had to the accompanying drawing, forming part thereof.

The figure is a plan view of a piece of linoleum, showing my new design.

I claim:

The ornamental design for linoleum, as shown.

WILLIAM J. DONNELLY.
